UNITED STATES PATENT OFFICE.

RUSSELL G. MILLER, OF PITTSBURGH, PENNSYLVANIA.

REVERSING VALVE.

Application filed December 15, 1921. Serial No. 522,673.

To all whom it may concern:

Be it known that I, RUSSELL G. MILLER, a citizen of the United States, residing at Pittsburgh, in the county of Allegheny and

5 State of Pennsylvania, have invented certain new and useful Improvements in Reversing Valves, of which the following is a specification.

10 My invention consists of an improvement in reversing valves for controlling the circulation of gases and air in furnace construction and use.

15 The invention is generally similar to the well known Siemens regenerative valve in that it is designed to operate in connection with such standard form of furnaces and flues, whereby to alternately direct the gas from the producer or other source to one end of the furnace or the other, and alternately open the return circulation to the stack or other outlet, the valve being operated alternately from time to time.

20 The object of the present invention is to simplify the construction of the valve by mounting it pivotally; to provide for water cooling of the valve and its parts; to provide for a close and accurate cut-off of the gas and simultaneous opening of the return flow without lost motion or leakage; and generally to produce a valve which is simple and economical in construction, adapted to effect the desired change in the gas currents with a minimum of movement, and to perform its functions in a satisfactory and workmanlike manner.

25 Referring to the drawings illustrating one preferred embodiment of the invention, Fig. 1 is a transverse vertical sectional view of the valve in position for drawing the gases to and from the opposite ends of the furnace;

30 Fig. 2 is a similar view showing the valve reversed for reverse flow;

35 Fig. 3 is a transverse vertical section on the line III—III of Fig. 1;

40 Fig. 4 is a view in side elevation of the valve; and

45 Fig. 5 is a detail view showing the valve provided with a facing of refractory material.

50 Referring to the drawing, the operating element for directing and altering the flow of the gases is pivotally mounted upon a foundation 2—2 comprising the upwardly extending terminal walls of flues 3—4 leading to opposite ends of a regenerative or

other furnace, at each side of the middle flue 5 leading to the stack or other outlet. The construction of such furnaces and of the gas inlet and outlet portions thereof 60 just referred to is too well known to require further description.

Extending upwardly above such foundation is a semicylindrical coping 6 providing a closure for the valve and having at 65 its upper portion a gas inlet fitting or flue 7 connected with the producer or other source of gas or air supply, and of any suitable construction with relation to cooperating valve mechanism or the like, as will be 70 readily understood.

At each side of the middle enclosed valve cavity, flanking the end portions of coping 6, and extending downwardly within the foundation walls 2—2 at each side, are the 75 end walls 8—8, providing closures for an interior space and the valve itself. End walls 8 are in the form of annular hollow boxes, preferably of cast iron or other suitable construction, whereby to provide for a 80 circulation of water therethrough by suitable inlet and outlet pipes 9—10 for cooling in the manner commonly practiced in similar constructions.

The inner and outer walls of the closures 85 8 are spaced sufficiently far apart to provide for ample water circulation, and are preferably shouldered as at a to provide for mounting on the brickwork of the walls for support. The end walls are centrally apertured, as shown, to provide for the extension therethrough of the end shafts 11 which are journaled in the bearings 12 at each side, one of such shafts 11 extending beyond the bearings and being provided with 90 a counter-weighted operating lever 13.

The valve proper consists of a hollow casting 14 extending across between the end walls 8—8 and connected by terminal flanges or heads 15 with similar rods or flanges 100 16 at the inner end of each shaft section 11. The valve 14 extends from its middle portion in opposite directions across the interior area within the end walls and coping 6, and its range of movement is limited by 105 abutments 17 at the upper inner portion of coping 6, at each side. At corresponding positions below the middle portion of the cavity are similar limiting shoulders 18—18 at the upper outer portion of boxes or blocks 110 19. These are preferably hollow and water cooled by means of circulating pipes 20, at

the point where the gas currents pass around at each side in their progress toward the stack. The inner faces 21 of boxes 19 are annular with relation to the pivotal center 5 of the valve 14, and the valve itself is provided with lateral annular extensions 22, forming continuations of the main valve, and serving as cut-off portions in cooperation with the inner faces of blocks 19.

10 The valve as thus constructed and mounted is capable of being thrown to one position or the other by the lever 13, the counter-weight 23 of which will hold the valve definitely in either position when thrown, as 15 illustrated in Fig. 4. The advantage of the annular extension 22 at each end portion of the valve is that it will preserve the sealing engagement between the valve and sealing face 21 of block 19, during the first portion of reverse movement, until the opposite end of the valve has come to the point of opening the circulation at the opposite side, at which time the opposite extension 22 will also be within close approach of the 25 other end of face 21 of the other block 18.

At the same time, the rising opposite end of the valve will have reached the closure position with relation to the upper incoming gas cavity, so that there will be no possibility of leakage or improper escape of gases at either side. As shown, the valve 14 extends outwardly beyond the lateral extensions 22 sufficiently far to provide a terminal abutting portion 24, which not only engages 30 against shoulders 17 and 18, but which also neatly interfits in the upper portion of its 35 swinging movement in the enlarged annular recesses 25—25.

At one side of the valve cavity, the coping 40 wall 6 is closed by a cleaning door box 26 having a hinged door 27 and an inner removable door 28, the inner face of which is annular and provides a neatly fitting closing wall for the terminal of the valve. By 45 this construction, the operation of the valve is provided for at each side in the same way, so that it is capable of being thrown to one position or the other to direct the gases from the producer to either end of the furnace, 50 and from either end of the furnace to the stack, as clearly indicated by the arrows.

The shaft sections 11, as shown, are hollow, communicating with the interior valve 14 at each inner end and at their outer ends 55 with water supply and exhaust pipes 29—30, with suitable fittings to provide for packing, as will be readily understood. By this means, ample cooling is ensured during the operation of the valve.

60 In Fig. 5 I show the hollow rotatable valve 14 provided on its upper side with a layer of brick or other refractory material 31 retained by terminal lugs 32 at each end, set inwardly from the valve edges for clearance of the abutting shoulders 17. By this

construction the valve is protected from destructive action of the incoming gases from the flue or port 7.

The construction and operation will be readily understood and appreciated from the foregoing description and the valve may be, of course, made in any suitable size, or it may be variously changed or modified in detail construction to adapt it to existing conditions or constructions by the skilled mechanic, but all such changes are to be considered as within the scope of the following claims.

What I claim is:

1. A reversing valve comprising a casing 80 having an inlet port, a middle outlet port, and outer circulation ports, and a pivotally mounted water cooled valve extending transversely across within the casing adapted to alternately open and close each circulation port with relation to the inlet and outlet ports respectively, and having water cooled lateral extensions adapted to be located alternately between the outlet port and either circulation port.

2. A reversing valve comprising a casing having an inlet port, a middle outlet port, and outer circulation ports and a pivotally mounted water cooled valve extending transversely across within the casing having laterally extending hollow portions adapted to occupy the space between the circulating ports and the outlet port.

3. A reversing valve comprising a casing 100 having a partly cylindrical interior and an inlet port, a middle outlet port, and outer circulation ports opening thereinto, a hollow reversing valve pivotally mounted midway across the interior of the casing having laterally extending continuously hollow arc-shaped portions, and seating members therefor located between the outlet port and the circulation ports.

4. A reversing valve comprising a casing 110 having a partly cylindrical interior and an inlet port, a middle outlet port, and outer circulation ports opening thereinto, hollow end walls at each end of the casing, a hollow reversing valve pivotally mounted midway across the interior of the casing having laterally extending annular portions, seating blocks therefor between the outlet port and the circulation ports, and means providing for water circulation through the end walls and the reversing valve.

5. A reversing valve comprising a casing having a partly cylindrical interior and an inlet port, a middle outlet port, and outer circulation ports opening thereinto, hollow end walls at each end of the casing, a hollow reversing valve pivotally mounted midway across the interior of the casing having laterally extending annular portions, seating blocks therefor between the outlet port and the circulation ports, hollow trunnions ex-

tending inwardly through the hollow end walls and connected with the reversing valve, bearings therefor, and means providing for water circulation through the end walls, reversing valve, and seating blocks.

6. In a reversing valve, the combination with a generally cylindrical casing provided with an inlet port, an opposite outlet port, an intervening circulation port at each side, 10 and a valve seat between each circulation port and the outlet port; of a reversing valve consisting of a hollow water cooled shell pivotally mounted centrally of the casing and having a lateral extension at each outer 15 swinging portion adapted to engage said valve seat at one side or the other of the outlet port.
7. In a reversing valve, the combination with a generally cylindrical casing provided 20 with an inlet port, an opposite outlet port, an intervening circulation port at each side, and a valve seat between each circulation port and the outlet port, of a reversing valve

consisting of a hollow water cooled shell pivotally mounted centrally of the casing 25 and having a lateral extension and abutment at each outer swinging portion adapted to engage said valve seat at one side or the other of the outlet port.

8. In a reversing valve, the combination 30 with a generally cylindrical casing provided with an inlet port, an opposite outlet port, an intervening circulation port at each side, and a valve seat between each circulation port and the outlet port, of a reversing valve 35 consisting of a hollow water cooled shell pivotally mounted centrally of the casing and having a hollow water cooled lateral extension and abutment at each outer swinging portion adapted to engage said valve 40 seat at one side or the other of the outlet port.

In testimony whereof I hereunto affix my signature.

RUSSELL G. MILLER.
